Assistant Examiner—Keli L Hill

(74) *Attorney, Agent, or Firm*—Plumsea Law Group, LLC

(73) Assignee: **Harman International Industries, Incorporated**, Northridge, CA (US)

(57) **CLAIM**

(**) Term: **14 Years**

The ornamental design for a lock for audio component controls, as shown and described.

(21) Appl. No.: **29/306,834**

DESCRIPTION

(22) Filed: **Apr. 17, 2008**

FIG. 1 is a perspective view of a lock for audio components controls showing our new design;

(51) **LOC (9) Cl.** **14-03**

FIG. 2 is a top plan view thereof;

(52) **U.S. Cl.** **D14/217; D8/331; D8/346**

FIG. 3 is a bottom plan view thereof;

(58) **Field of Classification Search** **D14/137, D14/155, 156, 168, 169, 170-172, 175, 176,**

D14/183, 188, 189, 193-198, 203.1-203.8,

D14/204, 207, 210, 217, 220, 238.1, 250,

D14/251, 341, 496; D8/330, 331, 346, 349,

D8/353; 455/90.1-90.3; 369/6-12; 370/342-344

See application file for complete search history.

FIG. 4 is a front elevational view thereof;

FIG. 5 is a rear elevational view thereof;

FIG. 6 is a side elevational view of one side thereof;

FIG. 7 is a side elevational view of the other side thereof;

FIG. 8 is an environmental perspective view of an exemplary audio component with dial controls; and,

FIG. 9 is a perspective view of the exemplary audio component shown with the lock for audio component controls arranged thereon.
